UNITED STATES PATENT OFFICE.

JOHN STODDART BROWN, OF GALVESTON, TEXAS.

TRUSSSED AXLE FOR WHEELED VEHICLES.

SPECIFICATION forming part of Letters Patent No. 591,736, dated October 12, 1897.

Application filed May 21, 1897. Serial No. 637,564. (No model.)

To all whom it may concern:

Be it known that I, JOHN STODDART BROWN, a citizen of the United States, residing at Galveston, in the county of Galveston and State 5 of Texas, have invented new and useful Improvements in Trussed Axles for Wheeled Vehicles, of which the following is a specification.

This invention relates to that class or type 10 of axles for wheeled vehicles wherein a metal truss rod or bar running longitudinally under the axle-body has its end portions extended through the axle-skeins and secured by screw-nuts which abut the outer ends of the skeins.

15 In the prior constructions it is essential to provide two independent screw-nuts at the outer end of each axle-skein, one designed to secure the end of the truss-rod and the other to retain the axle-box on the skein.

20 The chief object of my invention is to provide new and improved means whereby a single nut at the outer end of each axle-skein secures the extremity of the truss-rod and retains the axle-box on the wheel of the axle- 25 skein.

To accomplish this object, my invention consists in the combination, with an axle-body, of an axle-skein mounted thereupon and having an internally-screw-threaded 30 outer end, a truss-rod having one end arranged in the axle-skein, an axle-box rotatable on the skein, and a nut engaged with the truss-rod and the skein and retaining the axle-box on the latter.

35 The invention is illustrated by the accompanying drawings, in which—

Figure 1 is a sectional side elevation of an axle embodying my invention; and Fig. 2 is a longitudinal sectional view, on a larger 40 scale, of one end portion of the axle for the purpose of more clearly illustrating the construction of the parts.

In order to enable those skilled in the art to make and use my invention, I will now describe the same in detail, referring to the 45 drawings, wherein—

The numeral 1 indicates the axle-body, composed, preferably, of wood, but which may be of any material suitable for the purpose.

50 The end portions of the axle-body are provided with rigidly-attached axle-skeins 2, having collars 3 at or near their inner ends.

The outer extremity of each axle-skein is constructed with an internal screw-thread 4, into which screws the externally-screw-threaded 55 body 5 of a nut 6. The ends of the axle-body terminate a suitable distance from the outer extremities of the axle-skein to enable the screw-nuts to be screwed into the axle-skeins.

The axle-body is braced, reinforced, and 60 strengthened by the longitudinal metal truss rod or bar 7, preferably lying in a longitudinal groove in the under side of the axle-body and having its end portions extended through the axle-skeins. The extremities of the truss- 65 rod 7 are provided with screw-threads 8, running in the same direction and of the same pitch as the internal screw-threads 4 of the axle-skeins. The screw-threaded extremities 8 of the truss-rod engage a screw-threaded 70 socket formed through the center of the nut 6.

The nuts 6 screw upon the screw-threaded extremities 8 of the metal truss rod or bar at the same time that they screw into the outer ends of the axle-skeins in such manner that 75 while the screw-nuts engage the truss-rod and the axle-skeins they serve to retain the rotatable axle-boxes 9 upon the axle-skeins. The axle-boxes 9 are designed to be secured in the wheel-hubs in any suitable manner. 80 As here shown, a metallic washer 10 is arranged between the head of each nut and the outer extremities of an axle-skein and an axle-box. The washers 10 are each of a diameter greater than the diameter of the bore 85 of an axle-box, so that the washer will serve as an abutment to retain the axle-box upon the axle-skein. Obviously, however, the washers can be dispensed with and the heads of the nuts serve to retain the axle-boxes on 90 the axle-skeins. By the means described I dispense with one of the nuts ordinarily employed at each end of the axle and render a single nut susceptible of securing one end of the truss-rod and retaining one of the axle- 95 boxes on an axle-skein.

The truss-rod braces the axle-body and renders it strong, substantial, and durable, and the screw-nuts and internally-screw-threaded skeins provide novel, simple, efficient, and 100 economical means for obtaining the results stated.

Having thus described my invention, what I claim is—

1. The combination with an axle-body, of an axle-skein mounted thereupon, a truss-rod having one end arranged in the axle-skein, an axle-box rotatable on the skein, and a nut 5 engaged with the truss-rod and the skein and serving to retain the axle-box on the latter, substantially as described.
2. The combination with an axle-body, of axle-skeins mounted thereupon, a truss-rod 10 running longitudinally of the axle-body and extending through the axle-skeins, axle-boxes rotatable on the skeins, and screw-nuts having screw-threaded engagement with the truss-rod and axle-skeins and serving to re-15 tain the axle-boxes on the latter, substantially as described.
3. The combination with an axle-body, of an axle-skein mounted thereupon and having an internally-screw-threaded outer end, a truss-rod having one end arranged in the 20 axle-skein, an axle-box rotatable on the axle-skein, and an externally-screw-threaded nut screwed into the axle-skein and having a screw-threaded socket engaged with the end of the truss-rod, substantially as described. 25

In testimony whereof I have hereunto set my hand in presence of two subscribing witnesses.

JOHN STODDART BROWN.
